UNITED STATES PATENT OFFICE.

WILLIAM F. STREICH, OF DETROIT, MICHIGAN.

DRAWER-STABILIZER.

1,321,859.

Specification of Letters Patent. Patented Nov. 18, 1919.

Application filed August 12, 1919. Serial No. 316,998.

To all whom it may concern:

Be it known that I, WILLIAM F. STREICH, a citizen of the United States of America, and resident of Detroit, in the county of 5 Wayne and State of Michigan, have invented a new and useful Improvement in Drawer-Stabilizers, of which the following is a specification.

My invention relates particularly to the 10 drawers of filing cabinets adapted to the use of travelers and which while having papers filed therein, are shipped from place to place.

It is the object of my invention to provide 15 means for preventing the drawers from being shifted from their normal positions in the cabinet by the sudden and often violent changes in positions, of the cabinet in transit, and also to protect the extension guides 20 from being crushed or bent by blows upon the walls of the cabinet.

This object is obtained by the means described in the specification and illustrated in the accompanying drawings in which:

25 Figure 1, is a perspective view of a drawer provided with a stabilizer embodying my invention, the guide strips and the stabilizer being shown somewhat extended in order more clearly to illustrate them.

30 Fig. 2, is a perspective view upon an enlarged scale of the stabilizing device embodying my invention.

Fig. 3, is a detail perspective view of a modified form of my invention.

35 Fig. 4, is a view similar to Fig. 2 of the modification.

Fig. 5, is an end view looking from the opposite end of Fig. 4.

Referring to drawings, drawer A, has attached to it the usual strips a, which engage guides a', known in the trade as extension slides, and which are secured to the inner walls of the cabinet B.

The drawer stabilizer embodying my invention comprises two coöperating strips D, E, strip D being secured to the side wall of the cabinet adjacent to the guide a' and strip E being secured to the drawer adjacent to the strip a. Strip D, tapers from its top 45 d to its bottom d', and from its front to its rear, and adjacent to the lower face has formed in it a recess d'', which tapers from the front to the rear and forms an inclined flange d'.

Strip E is the complement of strip D in 55 forming an elongated rectangle.

In the modification illustrated in Figs. 3, 4 and 5, the stationary strip F has the form of two of the strips D, which have been placed side by side along their broader 60 longitudinal sides, and the movable strip G has the form of two of the strips E, placed side by side along their narrower sides. This forms upon the strip G, a longitudinal 65 centrally located double wedge shaped projection g and divergent flanges g', g'' and in the strip F forms a longitudinal tapering recess f which is the complement of the projection g.

In use, when the drawers, which are provided 70 with either of the forms of my strips, are closed, the complementary strips form longitudinal rectangles upon each side of the drawer and of a width equal to the distance between the side of the drawer and 75 the adjacent side wall of the cabinet. Thus the drawer is centralized, any play between the drawer and the cabinet is taken up and the guide strips, a, a' of the drawer are protected from injury due to any jamming 80 of the drawer. The drawer is also locked to prevent shifting in any direction when closed.

In drawing the drawer outward the tapering strips separate readily because the 85 drawer is being drawn in a counter wedge direction. In closing the drawer, there is no jamming action because the tapers and the flanges gradually center the drawer as it approaches its closed position.

90 While I have described by stabilizer as being formed of separate strips, it is apparent that they could be formed integral with the cabinet wall and the side of the drawer respectively and that it may be applied to sliding objects and their housings other than drawers and cabinets.

95 What I claim is:

1. A drawer stabilizer comprising two strips which when placed together form an 100 elongated rectangle, one of said strips having faces which taper from the front rearwardly, and the other of said strips being the complement of the former in forming the elongated rectangle.

105 2. The combination of a casing, a drawer, guides mounting the drawer in the casing, and a drawer stabilizer comprising strips

secured upon opposite sides of the casing and strips secured upon the drawer and contacting with the strips upon the casing the contacting faces of the strips tapering and forming wedges which coact in centering the drawer and holding it securely in the casing.

3. The combination of a casing, a drawer, guides mounting the drawer in the casing, 10 and a drawer stabilizer comprising strips secured upon opposite sides of the casing and strips secured upon the drawer and contacting with the strips upon the casing the contacting faces of the stationary strips 15 tapering longitudinally and transversely

from a vertical plane and the contacting faces of the other strips being the complement of said faces.

4. A drawer stabilizer comprising two strips which placed together form an elongated rectangle and the contacting faces of which are tapering and one of which has on it a tapering projection and the other a complementary recess which fits the projection. 20

In testimony whereof, I have hereunto subscribed my name this 9 day of August, 1919. 25

WILLIAM F. STREICH.
